US00D969873S

(12) **United States Design Patent** (10) **Patent No.:** **US D969,873 S**
(45) **Date of Patent:** **** Nov. 15, 2022**

(54) **DISPLAY SCREEN OR PORTION THEREOF WITH ICON**

(71) Applicant: **Samsung Electronics Co., Ltd.**, Suwon-si (KR)

(72) Inventor: **Hyunsoo Yuk**, Suwon-si (KR)

(73) Assignee: **SAMSUNG ELECTRONICS CO., LTD.**, Gyeonggi-Do (KR)

(**) Term: **15 Years**

(21) Appl. No.: **29/735,642**

(22) Filed: **May 22, 2020**

(30) **Foreign Application Priority Data**

Dec. 24, 2019 (KR) 30-2019-0062830

(57) **CLAIM**

The ornamental design for a display screen or portion thereof with icon, as shown and described.

DESCRIPTION

The FIGURE is a front view of a display screen or portion thereof with icon, showing our new design.

The outermost perimeter illustrated by a pair of dashed broken lines shows a display screen or portion thereof and forms no part of the claimed design.

The dot-dash broken lines in the figure illustrate a boundary of the claimed design, and form no part of the claimed design.
